UNITED STATES PATENT OFFICE

106,371

DESIGN FOR AN AIR CONDITIONING CABINET

Carl W. Pierson, Rockford, Ill.

Application August 16, 1937, Serial No. 71,131

Term of patent 7 years

To all whom it may concern:

Be it known that I, Carl W. Pierson, a citizen of the United States, residing at Rockford, in the county of Winnebago and State of Illinois, have invented a new, original, and ornamental Design for an Air Conditioning Cabinet, of which the following is a specification, reference being had to the accompanying drawing forming part thereof, the opposite side of the cabinet being substan-

tially like the side shown. The back of the cabinet is substantially plain.

In the drawing:

The figure is a perspective view of an air conditioning cabinet embodying my new design.

I claim:

The ornamental design for an air conditioning cabinet substantially as shown and described.

CARL W. PIERSON.
